UNITED STATES PATENT OFFICE.

ARTHUR TREVOR DAWSON AND GEORGE THOMAS BUCKHAM, OF WESTMINSTER, LONDON, ENGLAND, ASSIGNORS TO VICKERS LIMITED, OF WESTMINSTER, LONDON, ENGLAND.

BREECH MECHANISM OF ORDNANCE.

1,304,271.

Specification of Letters Patent. Patented May 20, 1919.

Application filed December 8, 1915. Serial No. 65,864.

To all whom it may concern:

Be it known that we, Sir ARTHUR TREVOR DAWSON, knight, and GEORGE THOMAS BUCKHAM, both subjects of the King of Great Britain, residing at Vickers House, Broad- 5 way, Westminster, in the county of London, England, have invented certain new and useful Improvements in or Relating to the Breech Mechanism of Ordnance, of which the following is a specification.

This invention relates to breech mechanism of the screw type in which the breech screw is rotatably mounted in a carrier (preferably swinging about a vertical hinge bolt or pin) whose rearward and forward movements open and close the breech opening. It has been proposed in such mechanism to employ a retaining catch mounted on the breech screw carrier and moved into engagement with the breech screw, when the carrier commences its rearward movement, by a toe-piece on the catch engaging with a bracket or the like on the gun, the said catch by meeting the face of the breech end of the gun during the inward or closing movement of the carrier, being moved to its disengaged position to enable the breech screw to be locked. In this manner during the rearward and forward movements of the carrier the angular position of the breech screw remains unchanged so that when the breech screw enters the breech chamber there is no liability of the threads on the screw fouling those in the chamber. Such an arrangement of catch results in considerable stress being placed on parts of the breech actuating mechanism during the slamming of the carrier. The chief object of the present invention is to provide a catch which will obviate this disadvantage.

According to this invention the positively actuated retaining catch mounted on the carrier is adapted to lie in the path of the crank pinion serving to operate the lever or arm connected to the breech screw. The said catch may be in the form of a lever one arm of which lies in a position transverse to the axis of the gun, and is adapted to engage with an arm or the like on the crank pinion. 45 In order that the said invention may be clearly understood, and readily carried into effect, we will describe the same more fully

with reference to the accompanying drawings in which:—

Figure 1 is a rear elevation and

55

Fig. 2 a sectional plan of a form of the improved retaining catch in position on breech mechanism of the kind to which the invention relates, this mechanism being well known and generally similar to that described in the specification of our prior British Patent No. 6485 of 1907. In these figures the breech screw is in the locked position.

Fig. 3 is a sectional rear elevation showing a portion of the breech screw carrier and the improved retaining catch on a larger scale than Figs. 1 and 2.

Fig. 4 is a side elevation, viewed from the right hand side of Fig. 3, of the bracket on the gun which serves to move the catch into contact with the arm on the crank pinion when the carrier commences its rearward movement, and

Fig. 5 is a section taken approximately on the line 1, 1 of Fig. 3. In Figs. 3 to 5 the catch is shown in the position it occupies when the breech screw is unlocked.

A is part of the breech screw carrier. B is the crank pinion of the breech actuating mechanism, this pinion having a roller b engaging in a slot or groove b' in the breech screw lever B' which serves to transmit angular locking and unlocking movements to the screw as is well understood. C represents the retaining catch and c represents its pivot pin connecting the catch to the lower flange of the breech screw carrier. C' represents the aforesaid transversely arranged arm of the catch C against which an arm B² on the crank pinion B is adapted to bear and C² represents the cranked arm of this catch. D represents the bracket on the breech face of the gun, in front of which bracket a toe-piece c² on the cranked arm C² is situated when the carrier is in its closed position.

The catch C is shown in Fig. 3 and by full lines in Fig. 5, in the position it occupies when the breech screw carrier is closed and the crank pinion B and the breech screw lever B' are shown in both figures in the position they assume when the breech screw is fully unlocked, the unlocking movement of the breech actuating mechanism, having

been limited as is well understood by a stop A^x, Figs. 1 and 2, engaging with a shoulder on the hinge bolt pinion, or by any other suitable device situated between the carrier 5 hinge bolt and the part with which the catch C engages. The arm B² of the crank pinion under these circumstances occupies in relation to the arm C' of the catch C, the position indicated in Fig. 3 and in full lines 10 by Fig. 5, the nose piece c² being situated in a cavity or recess d formed in the forward part of the aforesaid bracket D.

When the opening movement of the carrier is commenced the engagement between 15 the nose piece c² and an operating surface d^x on the bracket D effects a movement of the catch C into the relative position shown by chain lines in Fig. 5, in which position the arm C' of this catch lies against the arm 20 B² of the crank pinion B; this movement of the catch is limited by a projection c' thereon coming against a stop a on the carrier. The contacting surfaces of the arms C' and B² are inclined to facilitate coöperation and 25 to insure firm engagement between them. In this position of the parts the breech screw cannot be moved angularly from its unlocked position and any stresses caused by the slamming of the carrier are taken up between 30 the said two arms instead of between the roller b of the crank pinion B and the groove b' of the breech screw lever B' as is the case with the retaining catches heretofore employed.

35 The catch C may if desired be provided with a spring C³ for insuring the continued coöperation between the said arms C' and B² after the rearward displacement of the carrier has moved the toe-piece c² clear of the 40 bracket D.

As the carrier approaches the breech face during the closing movement the toe-piece c² will, if for any reason the catch C has become partly disengaged from the arm B², 45 operate with the inclined or rounded rear surface d' of the bracket D and the catch will thereby be displaced into its fully engaged position. As the closing movement of the carrier is being completed the front surface 50 of the crank arm C² of the catch C will come against the breech face of the gun and the catch will thus be displaced into the position shown by full lines in Fig. 5 with the nose-piece c² situated in the recess d of the bracket D. The arm C' then occupies a position 55 between the breech screw lever B' and the arm B² so that the crank pinion can then be displaced to lock the breech screw.

What we claim and desire to secure by 60 Letters Patent of the United States is:—

1. In a gun, the combination with the breech screw, its carrier and the crank pinion for angularly moving said breech screw through the intermediary of a lever connected to the breech screw and then moving 65

the carrier to the open position without any previous independent rearward movement of the breech screw, of a movable catch and means for positively moving said catch into the path of part of said crank pinion as the 70 carrier commences its opening movement.

2. In a gun, the combination with the breech screw, its carrier and the crank pinion for angularly moving said breech screw through the intermediary of a lever 75 connected to the breech screw and then moving the carrier to the open position without any previous independent rearward movement of the breech screw, of a movable catch and means for positively moving said catch into 80 the path of part of said crank pinion as the carrier commences its opening movement, and means for positively moving said catch out of the said path as the carrier completes its closing movement. 85

3. In a gun, the combination with the breech screw, its carrier and the crank pinion for angularly moving said breech screw through the intermediary of a lever connected to the breech screw and then moving 90 the carrier to the open position without any previous independent rearward movement of the breech screw, of a movable catch, an arm on said crank pinion, and means for positively moving said catch into the path 95 of said arm when the carrier commences its opening movement.

4. In a gun, the combination with the breech screw, its carrier and the crank pinion for angularly moving said breech 100 screw through the intermediary of a lever connected to the breech screw and then moving the carrier to the open position without any previous independent rearward movement of the breech screw, of a movable 105 catch, an arm on said crank pinion, and means for positively moving said catch into the path of said arm as the carrier commences its opening movement, and means for positively moving said catch out of the said path as the carrier completes its closing movement. 110

5. In a gun, the combination with the breech screw, its carrier and the crank pinion for angularly moving said breech screw 115 through the intermediary of a lever connected to the breech screw and then moving the carrier to the open position without any previous independent rearward movement of the breech screw, of a catch pivoted in said carrier, an arm on said crank pinion, and a bracket on the gun for positively rocking 120 said catch into engagement with said arm as the carrier commences its opening movement. 125

6. In a gun, the combination with the breech screw, its carrier and the crank pinion for actuating said breech screw, of a catch pivoted in said carrier, an arm on said crank pinion, and a bracket on the gun for posi- 130

tively rocking said catch into engagement with said arm as the carrier commences its opening movement, said catch being positively rocked into its disengaging position 5 by contact with the breech face of the gun as the carrier completes its closing movement.

7. In a gun, the combination with the breech screw, its carrier and the crank pinion 10 for actuating said breech screw, of a two armed lever, a vertical pivot for connecting said lever to the carrier, a projection on said crank pinion with which projection one arm of said lever is adapted to engage, and a bracket on the gun for engaging with the other arm of said lever to positively move the first mentioned arm into engagement 15 with the projection on the crank pinion as the carrier commences its opening movement.

8. In a gun, the combination with the breech screw, its carrier and the crank pinion 20

for actuating said breech screw, of a two armed lever, a vertical pivot for connecting said lever to the carrier, a projection on said 25 crank pinion with which projection one arm of said lever is adapted to engage, and a bracket on the gun for engaging with the other arm of said lever to positively move the first mentioned arm into engagement 30 with the projection on the crank pinion as the carrier commences its opening movement, said lever being positively moved into its disengaging position by the contact of the second mentioned arm with the breech face 35 of the gun as the carrier is completing its closing movement.

In testimony whereof we have hereunto affixed our signatures.

ARTHUR TREVOR DAWSON.
GEORGE THOMAS BUCKHAM.
